UNITED STATES PATENT OFFICE.

CARL SEVERIN JOHANSON, OF MONTCLAIR, NEW JERSEY.

EXTENSION-WINDOW GUIDE.

1,238,297.

Specification of Letters Patent. Patented Aug. 28, 1917.

Application filed January 25, 1917. Serial No. 144,496.

To all whom it may concern:

Be it known that I, CARL SEVERIN JOHANSON, a citizen of the United States, and a resident of 92 Walnut street, Montclair, in the county of Essex and State of New Jersey, have invented certain new and useful Improvements in Extension-Window Guides, of which the following is a specification.

10 This invention relates to extensible windows and especially to that class wherein a sash is secured to the outermost of a series of telescoping frames and guided by linearly extensible horizontal rods.

15 An illustration of a window wherein this invention may be used is found in my Patent No. 1,209,164, patented Dec. 19, 1916.

One advantage of this invention is to provide guides for an extensible window 20 which will be smooth in operation.

Another advantage is to provide window guides which are perfectly synchronous in action.

Another advantage is to provide an extensible window which is operated by pulling either of a pair of chains or cords.

Another advantage is to provide an extensible window which may be projected or retracted by pulling one of a pair of chains 25 or cords, or by turning a crank mounted upon a shaft rotatable by means of said chains or cords.

Further advantages and possibilities will become apparent as the specification proceeds.

Throughout the drawings, the same numerals or letters denote the same parts.

Figure 1 is an outer view of an apparatus embodying this invention. Fig. 2 is a vertical sectional view of Fig. 1, and is cut centrally through some parts. Fig. 3 is a diagrammatic top view of a modification. Fig. 4 is a similar view of Fig. 1. Fig. 5 is an interior view of Fig. 1, with part of 22 torn away.

50 My invention comprises primarily a hollow prismatic frame 22 bearing lip 27 and flange 31, by which latter it is secured to wall frame 30. Above frame 22 and beneath the same are a corresponding pair of large slots into which are fitted the flush plates 3 and 6. Secured to these are the square sleeves 9 and 9 and feed shafts 8 and 23. In these sleeves 9, 9, are slidably fitted the square rods 5 and 5, which carry sash 17 provided with glass 16 and screen frame

18 by means of blocks 13 and 13 and collars 14 secured to the vertical shafts on square collars 15.

Extending upward from screen frame 18 through slot 2 in plate 3 and through slot 9' in sleeve 9 is the vertical feed bar 11. Similarly, lower vertical feed bar 11 extends down from screen frame 18 through slot 6' in plate 6 and through slot 9' into sleeve 9. The feed bar 11 is secured to the frame 18 by means of bolt 10 and to guide bar 5 by extension and nut 5' in sleeve 9. The upper feed bar 11 is similarly secured to the corresponding parts.

70 The screw feed shafts 8 and 23 are mounted in bearings in the plates 6 and 3 and are provided with pulleys 7 and 4, respectively, by which they may be rotated. These pulleys are connected by a chain or cord denoted 21 and 29, providing for synchronous rotation of both shafts 8 and 23. If a handle 12 is used to rotate shaft 8 clockwise, the sash 17 and frame 18 will be drawn inward by means of feed bars 11 and 11 climbing 80 the threads of shafts 8 and 23, and passing inward in slots 9', 6', 2 and 9'. If the handle 12 is rotated anticlockwise, the frame 18 and sash 17 will be projected outward from the building, the action being correspondingly opposite to that of the previous case.

It is not imperative to use handle 12, however, as the above operations may be performed by merely pulling either cord 21 or 90 29, in which case the handle may be dispensed with.

The rollers 1' in stop 1, 19 and 25 in sleeves 9 and 9 and 20 and 26 in guide bars 5 and 5 are all intended to reduce the friction and increase smoothness of operation generally.

95 In Fig. 5 the hinged frame 24 is shown opened to expose flange 31, wall facing 30, and plates 6 and 3. Frame 24 fits snugly 100 about the edges 28 of frame 22 when closed, as in Fig. 2. The plates 8' and 8' are set in frame 24 to aid in supporting shaft 8 when rotating the latter by handle 12.

105 It will be noted that if chains or cords 21, 29 were spread apart to present positions immediately within edges 28, as indicated by dotted lines *ac* and *bd*, the principle involved is not altered in any manner. In this case it would be necessary to introduce 110 pulleys as indicated at points *a*, *b*, *c*, *d*, the purpose being to remove 21 and 29 from a

central position to accessible side positions where they would not obstruct or mar the view.

If screen frame 18 should be detached 5 from sash 17, the latter would be free to swing into any position if guides 5, 5, be extended a distance outward, as illustrated in Fig. 4.

In Fig. 3 the guide 5 is shown as being 10 on one side rather than in the center, the result being that sash 17 would be able to swing more to one side if the frame 18 is detached, than were the guide 5 centrally located.

15 In Fig. 5 edge 28 has been torn away at $\frac{1}{2}$ to expose slot 6' in plate 6 and to especially illustrate the position of said plate in relation to base surface s in which 6 is fitted flush. The rear parts of screen frame 20 18 and feed bar 11 which should be evident in $\frac{1}{2}$ have been omitted to clearly show slot 6' in plate 6.

Having thus fully described my invention, what I claim as new and desire to obtain by Letters Patent is:

1. A window including an extensible frame bearing a sash, guide rods adapted to slide horizontally secured at their outer ends to said sash, and at their inner ends to bars 30 extending to the inner extremity of said extensible frame, means for supporting said guide rods, and means for reciprocating said rods.

2. A window including an extensible 35 frame bearing on its outer edges a sash as an integral part thereof, slid able horizontal guide rods secured at their outer extremities to said sash, and at their inner extremities to bars secured to the inner edges of 40 said extensible frame, a feed nut on each of said bars and horizontal screw feed shafts engageable by said feed nuts, said shafts being adapted for manual rotation and horizontal supports for said guide rods.

45 3. A window including an extensible frame and horizontally slid able guide rods

attached at their outer ends directly to said frame, and at their inner ends to bars provided with feed nuts secured to the inner edges of said frame, screw feed shafts engageable by said feed nuts, and longitudinally slotted bearing plates supporting and concealing said feed shafts, said feed nuts communicating through said plates from said shafts to said frame.

4. A window including an extensible frame and horizontally disposed guide bars attached at both extremities to said frame to provide support therefor in horizontal movement, plates bearing screw feed shafts 60 disposed parallel to said bars, and feed nuts secured to the latter to provide longitudinal movement thereof upon rotating said screw feed shafts, extensions upon said plates to provide supports for said guide 65 bars there being pulleys on said shafts and a cord connecting said pulleys to provide synchronous rotation of said shafts.

5. A window including a horizontally 70 slidable frame riding on horizontal guide bars secured thereto at both extremities, screw feed shafts arranged parallel to said bars and supported by longitudinal plates provided at the extremities with bearings therefor, sleeves with rollers secured to said 75 plates provided and adapted to receive said guide bars, and feed nuts engaging said feed shafts secured to the inner extremities of said guide bars, there being slots in said sleeves and plates to provide passage for the 80 connections between said inner extremities of the guide bars and aforesaid slidable frame.

Signed at 132 Nassau street, in the borough of Manhattan in the county of New 85 York, city and State of New York, this 23rd day of January, A. D. 1917.

CARL SEVERIN JOHANSON.
